[57] **CLAIM**

The ornamental design for a flashlight, as shown and described.

DESCRIPTION

FIG. 1 is a front and top left perspective view of a flashlight with the switch button depressed to turn on the flashlight, showing my new design;

FIG. 2 is a front elevational view thereof showing the flashlight prior to being turned on;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a cross sectional view taken along the line VII—VII of FIG. 3.

The rear elevational view is a mirror image of the front elevational view shown in FIG. 2.
